ILLUMINABLE COMPACT

Edward Atino, Washington, D. C., and
Pedro Engardio, Williamston, Mich.

Application February 27, 1950, Serial No. 8,164

Term of patent 3½ years

(Cl. D86—10)

To all whom it may concern:

Be it known that we, Edward Atino and Pedro Engardio, citizens of the United States, residing respectively, at the city of Washington, District of Columbia, and of Williamston, in the county of Ingham and State of Michigan, have invented a new, original, and ornamental Design for an Illuminable Compact, of which the following is a specification, reference being had to the accompanying drawing, forming part thereof.

Figure 1 is a perspective view of an illuminable compact showing our new design; the cover being shown in open position.

Figure 2 is a top plan view with the cover closed.

Figure 3 is a side elevational view thereof.

Figure 4 is an end elevational view looking in the direction of the arrows 4—4, Figure 2.

We claim:

The ornamental design for an illuminable compact, as shown.

EDWARD ATINO.
PEDRO ENGARDIO.
